UNITED STATES PATENT OFFICE.

WILLIAM O. BATT, OF GRANITE, COLORADO.

LAMP.

1,084,126.

Specification of Letters Patent. Patented Jan. 13, 1914.

Application filed May 31, 1913. Serial No. 771,053.

To all whom it may concern:

Be it known that I, WILLIAM O. BATT, a citizen of the United States, residing at Granite, in the county of Chaffee and State of Colorado, have invented certain new and useful Improvements in Lamps, of which the following is a specification, reference being had therein to the accompanying drawings.

10 The lamp provided by this invention particularly is adapted for use in association with railway-signals, but it also may be used for other purposes.

It is an object of the invention to provide 15 a lamp that will not blow out even in the highest winds, that will keep the illuminating fuel therein at a sufficiently high temperature to prevent freezing or semisolidification in very cold weather, and that will 20 illuminate a station-platform without confusing the signal-light therefrom.

When read in connection with the description herein, the details of construction and arrangement of parts contemplated by the 25 invention will be apparent from the accompanying drawing, forming part hereof, wherein there are disclosed for purposes of illustration embodiments of the invention 30 adapted for use with semaphore railway-signals.

While the embodiments disclosed now are considered preferable ones, it is to be understood that it is not the intention to be limited necessarily to the exact delineations herein 35 in interpretation of claims hereinafter, as it is obvious that alterations may be made within the limits of the claim without departing from the nature and spirit of the invention.

40 Like reference-characters refer to corresponding parts in the views of the drawings, of which—

Figure 1 is an elevation as seen from one side; Fig. 2 is a longitudinal sectional view 45 thereof; Fig. 3 is an elevation as seen from another side, in which is embodied an arrangement for throwing light downwardly; Fig. 4 is a sectional view on the line 4—4, Fig. 1, looking up; Fig. 5 is a sectional view 50 on the line 5—5, Fig. 3, looking down, an arrangement for throwing light downwardly being shown; Fig. 6 is a view in elevation of a modification; and Fig. 7 is a sectional view thereof.

55 Referring more particularly to the draw-

ings, 8 designates a frame comprising substantially parallel normally vertical rods 9 removably secured at their upper ends by nuts 10 to a cross piece 11, and having their lower ends deflected laterally and formed 60 with eyes 12.

Carried on the frame is a lamp device that includes an air-tight lamp-chamber casing 13. Positioned in the casing at opposite places in its sides are light-tubes 14, which have screwed thereinto lens or target carrying members 15. A lamp 16, including a fuel-reservoir 17 and a burner 18 supplied with fuel from the reservoir, (Figs. 1 and 2), is positioned in the casing in such manner that the burner will show light through the light-tubes, and it is removable and replaceable through an opening in the bottom of the casing.

A flue 19 extends upwardly from the central portion of the top of the casing 13. Air-conduits 20 lead through the top of the casing to places in the lower part of the interior thereof in proximity to the fuel-reservoir for the purpose of supplying to the burner the 80 air necessary for combustion. The upper ends of the flue and air-conduits are disposed in a straight line.

In order to prevent the lamp-flame from 85 being subjected to air-blasts from outside the casing sufficiently strong to blow it out and to supply air only from a protected heated source to the lamp-chamber in the vicinity of the fuel-reservoir to keep the fuel therein above the freezing point, there is positioned above the lamp-chamber a hollow air-tight casing 21, preferably cylindrical, and having its ends 22 removable to afford 90 access to the interior for cleaning. The casing 21 is divided into an upper or air-heating 95 compartment 23 and a lower or flue-compartment 24 by a substantially horizontal diametrically-positioned partition 25. Leading upwardly into the lower compartment is a central flue 19^a arranged to slip over or into flue 19 and to constitute an extension thereof.

On each side of flue 19^a and near an end of the casing 21 is an air-conduit 20^a leading from the upper compartment downwardly through the lower compartment to the exterior of the casing, where it is arranged to slip into or over one of air-conduits 20 and to be held thereto by set-screws 26, the conduits 20^a thus constituting extensions of conduits 20. The casing 21 is supported on 100 105 110

casing 13 by this engagement of flue 19 and conduits 20 with the extensions 19^a and 20^a, and the flue and conduits form continuous passages between the casing 21 and the lamp-chamber. Vents 27 open from the lower or flue compartment to the atmosphere, and air-conduits 28 lead from the atmosphere through the lower compartment to the upper or air-heating compartment.

10 When the lamp is burning, the products of combustion and heated air rise to the lower compartment through the flue 19—19^a and have their exit through vents 27, and hot fluids in the lower compartment heat 15 the air in the upper compartment and in the air-conduits 28. The draft created by the burning lamp operates to draw heated air into the lamp-chamber through conduits 20—20^a from the upper compartment, and 20 the heated air is discharged into that chamber at the lower ends of the conduits in the vicinity of the lamp-reservoir, whereby the reservoir is warmed. Air is supplied to the upper compartment through the tubes 28 25 which extend through the lower compartment and in which it receives its initial warming.

If desired for the purpose of affording illumination to a station-platform or other 30 place below the lamp, the arrangement may be such as is illustrated by Figs. 3 and 5 or as is illustrated by Figs. 6 and 7.

As shown by Figs. 3 and 5, a lamp 16^a has a reservoir 17^a through which is an enlarged central vertical opening 29 to the center of which extends from the reservoir a wick-tube and burner 18^a arranged to show light through the targets and downwardly through the opening, and the opening below 35 the burner is closed by glass or other suitable translucent material 30. Thus it will be seen that by this arrangement light from the burner is thrown downwardly as well as laterally through the targets. In order to 40 prevent the downwardly-directed light from being seen too distinctly from the sides and becoming confused with light from the targets, an outwardly and downwardly flaring 45

shade and reflector 31 is attached to the reservoir.

As shown by Figs. 6 and 7, the lamp device includes a lamp-chamber casing 13^b, which is of substantially double-truncated-cone shape or bulged intermediate its top and bottom. The lower portion 32 of the 55 casing is made of glass or other translucent material, in the vertex of which the reservoir 17^b of a lamp 16^b is held by rods or other suitable supports 33, the arrangement being such that light from a burner 18^b is shown 60 downwardly as well as laterally through the targets. In order to shade the downward light at the sides, an outwardly and downwardly flaring shade and reflector 31^b is attached to the lower portion of the lamp-chamber casing.

The lamp device is placed and held on the frame 8 by having a frame-rod 9 on each side passed upwardly through eyes 34 on the lamp-chamber casing 13 and on upper casing 70 21 and then secured to cross piece 11 by nuts 10, the weight of the lamp device being sustained by the eyes on the lamp-chamber casing resting on the laterally-deflected eyes 12 and the lamp being held in upright position by the eyes on the casing 21.

Having thus described my invention, what I claim as new, and desire to secure by Letters Patent, is—

A lamp device having a lamp-chamber, a 80 casing having a partition dividing its interior into a flue-compartment and a heating-compartment, a flue leading from said lamp-chamber to said flue-compartment, there being a vent to the atmosphere from 85 said flue-compartment, a conduit leading from the atmosphere through said flue-compartment to said heating-compartment, and a conduit leading from said heating-compartment to said lamp-chamber.

In testimony whereof, I affix my signature in presence of two witnesses.

WILLIAM O. BATT.
